UNITED STATES PATENT OFFICE.

WILLIAM BEALL GRAY, OF LOUISVILLE, KENTUCKY, ASSIGNOR TO MARTIN J. BANNON, OF LOUISVILLE, KENTUCKY.

PIPE-SUPPORT.

1079,758.

Specification of Letters Patent. Patented Nov. 25, 1913.

Application filed July 13, 1912. Serial No. 709,262.

all whom it may concern:

Be it known that I, WILLIAM B. GRAY, a citizen of the United States, and a resident of Louisville, in the county of Jefferson and State of Kentucky, have invented a new and Improved Pipe-Support, of which the following is a full, clear, and exact description.

My invention is an improvement in traveling supports for pipes, and has for its object the provision of a safe and simple device of the character specified, for supporting heating and power pipes, wherein means is provided for permitting the expansion 15 and contraction of the pipes without injury to the pipe or to the support.

Referring to the drawings forming a part hereof:—Figure 1 is a side view of the support with the pipe in place, Fig. 2 is a section on the line 2—2 of Fig. 1, Fig. 3 is a perspective view of the base of the support, Fig. 4 is a perspective view of the carrier with the pipe removed, and Fig. 5 is a vertical longitudinal section of the pipe and 25 support.

The present embodiment of the invention comprises a base or cradle, consisting of a substantially rectangular frame, composed of end members 1 and side members 2, the 30 end members extending beyond the side members at each side of the carrier as shown at 3. The extended portions 3 of the end members are rounded on their under faces as shown at 4.

Each of the side members 2 is slotted as 35 shown at 5, for the sake of lightness, and while the upper edges of the side members are flush with the upper edges of the end members, the said side members are 40 cut away on the under side of the base as shown more particularly in Fig. 5. The end members are connected between the side members by a pair of rack bars 6, each rack bar being integral at its ends with the end 45 members, and the teeth of each rack bar are in register with the teeth of the adjacent bar. The rack bars are also integral with the side members at their outer sides for the sake of strength as shown in Fig. 2. 50 A slot 7 is provided between the rack bars and the under faces of the rack bars are flush with the lowest portion of the ends 3 of the end members.

A movable support, carriage, or saddle 8 is provided for receiving the pipe 9, the said pipe having the usual non-heat conducting covering 10, secured thereto by straps 11. The carriage is concave on its upper face to fit the covering as shown at 12, and each side edge thereof is provided with spaced 60 openings or slots 13 for permitting the connection of the ends of holding wires 14.

Each of the holding wires is connected at its ends with an opening 13, the said wires passing over the covering to secure the pipe to the carriage. The carriage is provided with a central longitudinally extending rib 15 on its lower face and with a series of rack teeth 16 at each side of the rib, the said teeth being spaced to correspond with the 70 teeth of the rack bars 6.

A pair of toothed wheels 19 are arranged between the carriage and the rack bars, each wheel meshing with a rack bar 6 of the base and with the adjacent series of teeth 16 of the carriage. The rollers are connected by a shaft 20, and the inner face of each roller is flush with the inner edge of the rack bar with which it engages. The rib 15 extends between the wheels as shown in 80 Figs. 1 and 2, and the arrangement of the rack bars 6 with respect to the base provides a stop at each end of each rack bar. The said stop is the inner face of the adjacent end member 1, and the said faces limit the 85 travel of the wheels. The carriage is connected directly with the pipe by means of a block or key 21, arranged in a recess 22 at the center of the upper face of the carriage, and having at its upper end an arc-shaped bearing plate 23, for engaging the pipe. The covering 10 of the pipe is cut away to receive the key and the bearing plate as shown in Figs. 2 and 5.

The rollers may be secured to the shaft 20, 95 in any desired manner, and the said rollers travel in a pocket or depression in the cradle. It will be evident that the upper surface of the carriage or saddle corresponds with the curvature of the pipe so 100 as to fit the said pipe closely. When the pipe is not covered, the key or block 22 and the bearing plate 23 are removed. The object of the key or block is to prevent bending of the pipe by compression of the covering. The key or block engages the pipe di-

rectly and transfers the weight directly to the carriage or saddle, thus relieving the covering or insulation from pressure.

It will be evident that the pipe may travel 5 twice the length of the rack bar or of a series of teeth. The cradle and the saddle may be of any desired length, to afford a suitable support and to permit the necessary amount of travel. The rib 15 by its en- 10 gagement with the space between the rollers and the arrangement of the rollers in the pocket or depression of the cradle, prevents any binding or skewing of the parts with respect to each other. The pipe must travel 15 longitudinally and cannot move laterally. The provision of duplicate rollers, rack bars and series of teeth lightens the device, as a whole, and permits dirt or leakage to fall through the slot 7 without interfering with 20 the operation of the device.

It will be obvious that the carriage or saddle might be divided into a plurality of beds for carrying a number of pipes side by side without departing from the spirit 25 of the invention. The rib 15 also prevents the saddle from creeping laterally, holding it in its proper position with respect to the rollers. With the present construction the weight of the pipe and its resistance to 30 thrust is distributed evenly throughout the extent of the pipe. The cradle or carriage cannot shift from its position laterally neither can it rock, and as a whole, there is a minimum of weight for the necessary 35 strength.

It is obvious that many changes might be made in the construction without departing from the spirit of the invention as specified in the appended claims.

40 It will be understood that the gear wheels above mentioned are preferably integral, that is, the wheels are in fact a roller having a series of teeth at each end separated by the groove for receiving the rib. It is ob- 45 vious however, that the wheels may be separate if desired.

I claim:—

1. A device of the character specified, comprising a cradle having in its upper face 50 a substantially rectangular depression and having a rack bar at each side of the depression, extending longitudinally of the cradle, said rack bars being spaced apart from each other, a carriage for the pipe, the 55 upper face of the carriage being concave transversely to fit the insulation of the pipe to be supported and having a central recess, said carriage having on its under face a longitudinal central rib and a series of gear 60 teeth on each side of the rib, a pair of gear wheels arranged between the carriage and the cradle, each wheel meshing with a rack bar and with the adjacent series of teeth on the carriage, the rib of the carriage extending 65 between the wheels, a shaft connecting

the said wheels, the carrier having an opening at each side edge near each end thereof, for receiving the end of a holding wire to hold the pipe on the carriage, and a block adapted to be seated in the recess of the carriage and having a bearing plate for engaging the pipe, said block being adapted to extend through the insulation of the pipe to engage the pipe directly.

2. A device of the character specified, 70 comprising a cradle having in its upper face a substantially rectangular depression and having a rack bar at each side of the depression, extending longitudinally of the cradle, said rack bars being spaced apart 75 from each other, a carriage for the pipe, the upper face of the carriage being concave 80 transversely to fit the insulation of the pipe to be supported and having a central recess, said carriage having on its under face a longitudinal central rib and a series of gear teeth on each side of the rib, a pair of gear 85 wheels arranged between the carriage and the cradle, each wheel meshing with a rack bar and with the adjacent series of teeth on the carriage, the rib of the carriage extending 90 between the wheels, a rigid connection between the wheels, and a block seated in the recess and extending above the carriage 95 a distance corresponding to the thickness of the insulation on the pipe.

3. A device of the character specified, comprising a cradle having spaced longitudinally extending series of teeth on its upper face, a carriage for the pipe, the upper 100 face of the carriage being concave transversely to fit the insulation of the pipe to be supported, said carriage having on its under face a longitudinal central rib and a series of gear teeth on each side of the rib, a 105 pair of rigidly connected spaced gear wheels arranged between the carriage and the cradle, each wheel meshing with a series of gear teeth on the carriage and a series of gear teeth on the cradle, the rib of the carriage 110 extending between the wheels, the carriage having a recess in its upper face, and a block seated in the recess and extending above the carriage a distance corresponding to the thickness of the insulation on the pipe.

4. A device of the character specified, comprising a cradle having spaced longitudinally extending series of teeth on its upper face, a carriage for the pipe, the upper 120 face of the carriage being concave transversely to fit the insulation of the pipe to be supported, said carriage having on its under face a longitudinal central rib and a series of gear teeth on each side of the rib, a 125 pair of rigidly connected spaced gear wheels arranged between the carriage and the cradle, each wheel meshing with a series of gear teeth on the carriage and a series of gear teeth on the cradle, the rib of the car- 130

riage extending between the wheels, and a block seated on the upper face of the saddle and extending above the said face a distance corresponding to the thickness of the insulation on the pipe.

5. A device of the character specified, comprising a cradle, having laterally spaced longitudinally extending series of gear teeth on its upper face, a carriage having its upper face concave transversely to fit the pipe to be supported, and having on its under face a pair of laterally spaced longitudinally extending series of gear teeth, a pair of rigidly connected gear wheels arranged between the carriage and the cradle, each wheel meshing with a series of teeth on the cradle, and a series of teeth on the carriage, the carriage having a longitudinal rib between the series of teeth, said rib extending between the wheels.

6. A device of the character specified, comprising a cradle, having laterally spaced longitudinally extending series of gear teeth on its upper face, a carriage having its upper face concave transversely to fit the pipe to be supported, and having on its under face a pair of laterally spaced longitudinally extending series of gear teeth, a pair of rigidly connected gear wheels arranged between the carriage and the cradle, each wheel meshing with a series of teeth on the cradle, and a series of teeth on the carriage, said cradle having means for limiting the lateral and longitudinal movement of the wheels, and the carriage having means for preventing lateral movement thereof with respect to the wheels.

7. A device of the character specified, comprising a cradle, having laterally spaced longitudinally extending series of gear teeth on its upper face, a carriage having its upper face concave transversely to fit the pipe to be supported, and having on its under face a pair of laterally spaced longitudinally extending series of gear teeth, a pair of rigidly connected gear wheels arranged between the carriage and the cradle, each wheel meshing with a series of teeth on the cradle, and a series of teeth on the carriage, said cradle having means for limiting the lateral and the longitudinal movement of the wheels.

8. A device of the character specified, comprising a cradle having laterally spaced longitudinally extending series of gear teeth on its upper face, a carriage having its upper face concave transversely to fit the pipe to be supported, and having on its under face a pair of laterally spaced longitudinally extending series of gear teeth, a pair of rigidly connected gear wheels arranged between the carriage and the cradle, each wheel meshing with a series of teeth on the cradle,

and a series of teeth on the carriage, said carriage having means for preventing lateral movement thereof with respect to the wheels.

9. A device of the character specified, comprising a cradle, having a longitudinal series of transverse gear teeth on its upper face, a carriage having its upper face concave transversely to fit the pipe to be supported and having on its under face a series of longitudinally extending gear teeth, a gear wheel arranged between the carriage and the cradle and meshing with both series of teeth, said carriage having means for preventing lateral movement thereof with respect to the wheel and the cradle having means for preventing lateral movement of the wheel with respect to the cradle and means for limiting the longitudinal movement of the wheel.

10. A device of the character specified, comprising a cradle, having a substantially rectangular pocket in its upper face, a carriage having a concave upper face for receiving the pipe, a roller arranged between the cradle and the carriage in the pocket, the carriage having means for preventing lateral movement with respect to the roller.

11. A device of the character specified, comprising a cradle having spaced series of teeth, a carriage for the pipe having spaced series of teeth, and a roller having spaced annular series of teeth for meshing with the adjacent series of the cradle and the carriage, the series of the roller being separated by an annular groove and the carriage having a rib between the series for engaging the groove.

12. A device of the character specified, comprising a cradle having a longitudinally extending series of teeth, a carriage for receiving the pipe having a series of teeth extending longitudinally of the pipe, and a roller between the carriage and the cradle and having teeth meshing with the teeth of the carriage and the cradle, said cradle having means for preventing longitudinal movement of the roller and the carriage and the roller having means for preventing movement of the carriage longitudinal to the roller.

13. A device of the character specified, comprising a cradle having a longitudinally extending series of teeth, a carriage for receiving the pipe having a series of teeth extending longitudinally of the pipe, and a roller between the carriage and the cradle and having teeth meshing with the teeth of the carriage and the cradle.
